SLEET CUTTER

Rudolph Malpert, Fargo, N. Dak.

Application May 16, 1947, Serial No. 748,408

2 Claims. (Cl. 36—62)

1

This invention relates to a creeper adapted to be worn on overshoes or rubbers to keep the wearer from slipping on the ice.

It is an object of the present invention to provide a creeper wherein the cutting elements will be self cleaning and wherein the strap or band to which the cutting elements are attached can be adjusted inwardly upon the cutting elements to fit the creeper to different size shoes or rubbers.

Other objects of the present invention are to provide a creeper adapted for use on overshoes which is of simple construction, inexpensive to manufacture and efficient in operation.

For other objects and for a better understanding of the invention, reference may be had to the following detailed description taken in connection with the accompanying drawing, in which

Fig. 1 is a side elevational view of a rubber with an ice creeper embodying the features of the present invention connected thereto.

Fig. 2 is a bottom view of the ice creeper with portions of the band broken away to show the connection of the creeper elements therewith.

Fig. 3 is a rear elevational view of the rear creeper element and Fig. 3a is a bottom plan view of the element.

Fig. 4 is a front elevational view of one of the other creeper elements and Fig. 4a is a bottom plan view of this creeper element.

Fig. 5 is a transverse cross-sectional view taken on line 5—5 of Fig. 4.

Fig. 6 is a rear elevational view of the entire creeper assembly.

Fig. 7 is a longitudinal cross-sectional view taken on line 7—7 of Fig. 6.

Referring now to the figures, 10 represents a rubber or overshoe to which my creeper device is fitted. This device comprises a wide band 11 of U-shape having an intermediate groove portion 12 adapted to receive the edge 13 of the heel of the rubber 10. The forward part of the band or leg portions thereof have slots 14 through which a strap 15 is extended and fastened by a buckle 16 over the forward part of the rubber to secure the creeper upon the heel against rearward displacement.

This band 11 is made of steel and its leg portions can be flexed inwardly or outwardly to adjust the same to different size heel edges 13. In the rear of the band is a fixed and permanently secured cutting element 18 having a cutting edge 19 and cut-a-way portions 21 and 22 respectively forwardly and rearwardly thereof. This cutting element 18 extends below the bottom edge of the band 11 and is engaged upon its top part by the bottom of the rubber heel.

2

Other cutting elements having a similar cutting edge 23 and cut-a-way portions 24 and 25 are disposed between the leg portions of the band at longitudinally spaced locations forwardly of the cutting element 18. These cutting elements are indicated at 26 and 27. Each of these cutting elements have a threaded portion 28 extending from each of their ends and through openings 29 in the band. On each threaded portion are washers 31 and lock nuts 32 for adjustably securing the band on the threaded portion so that the legs of the band can be adjusted to different positions on the cutting elements and so as to adapt the band to different size heels 13. The threaded portions 28 lie flush with the upper edge of the cutting elements so that the cutting edges 23 will be offset downwardly therefrom. The cutting edges of all of the cutting elements extend below the bottom edge of the band.

While various changes may be made in the detail construction, it shall be understood that such changes shall be within the spirit and scope of the present invention as defined by the appended claims.

25 I claim:

1. An ice creeper comprising a band adapted to fit about the heel of an overshoe or rubber and to extend downwardly from the bottom thereof, cutting elements secured between the legs of the band and extending downwardly from the bottom edge of the band for engagement with the ice, and a strap adapted to extend from the leg portions over the front of the shoe, and said cutting elements having threaded portions on the opposite ends of the same adapted to extend through the leg portions of the band, and lock nuts for fixing the band at its adjusted position to the threaded portion of the cutting elements whereby the band can be adjusted to different width

30 2. In an ice-creeper, a plurality of removable and replaceable ground-engaging elements each comprising a transversely extending body portion having blades formed in the lower face thereof and an outwardly extending threaded attaching lug at either end of said body.

RUDOLPH MALPERT.
